UNITED STATES PATENT OFFICE.

EDWIN F. BANFIELD, OF ATLANTIC HIGHLANDS, NEW JERSEY.

ELEVATOR CONTROL.

1,386,223.

Specification of Letters Patent.

Patented Aug. 2, 1921.

Application filed December 11, 1918. Serial No. 266,216.

To all whom it may concern:

Be it known that I, EDWIN F. BANFIELD, a citizen of the United States, residing at Atlantic Highlands, in the county of Monmouth and State of New Jersey, have invented new and useful Improvements in Elevator Controls, of which the following is a specification.

This invention relates to improvements in elevator controls.

One of the objects of this invention is to provide an improved safety control for preventing the operation of the elevator car unless the car door is closed.

Another object is to provide an electrical safety control whereby the open condition of the car door prevents the operation of the elevator.

Another object is to prevent the inadvertent starting of the elevator during inspection, cleaning, adjusting, repairing, etc., while the car door is open.

A further object is to provide for the automatic adjustment of the safety mechanism.

Another object is to provide a safety control which may be readily applied to existing elevator equipment.

Other objects and advantages will appear from the specification and claims.

One embodiment of the invention is illustrated in the accompanying drawing, wherein—

Figure 1 shows, diagrammatically, the invention associated with an electrical elevator system, and.

Fig. 2 shows a modification of one of the features.

In its preferred embodiment the invention comprehends a flexible cable extending along the elevator shaft in a position to be under the control of the car door in any position of the car. This cable actuates a safety switch which causes the operating motor to be disconnected from the line, to stop the car whenever the door is opened while the car is in motion, or to prevent the starting of the car, if it is at rest, until the door is closed. To guard against the inadvertent starting of the car, by the manipulation of any part of the ordinary controller system, during inspection, cleaning, adjustment, repairs, etc., while the door is open, a master switch is provided for entirely removing the power from the controller system until the door is closed. Automatic adjusting and compensating means are also

provided to insure that the correct relation exists between the cable and safety switch so that the control is always able to function properly.

Fig. 1 will first be described.

An elevator car 5 is adapted to be moved up and down in the elevator shaft or hatchway by an electric motor 6. The up-and-down movement is regulated by an operator's-controller 7, carried in the car, through a pair of electromagnetic direction switches 8 and 9. The power for operating the motor is supplied through a master switch 10 and is controlled by a series of accelerating switches 11, 12, 13 and 14. A flexible cable 15 extends along the elevator shaft and is actuated by the car door to control the condition of a safety switch 16. When the door is open the safety switch is also open. If the door is opened while the car is in motion the safety switch causes the immediate opening of the direction switch and the master switch and the car is stopped. If the car is at rest the opening of the door causes the safety switch to open the master switch and the car cannot be started until the door is closed.

The flexible cable 15 is secured to the top of the elevator shaft and extends between two pairs of rollers 17 and 18 carried in fixed positions on the car. The cable also passes between a pair of rollers 19 secured to the free end of a gate-actuated lever 20. The cable and lever assume the positions shown in full lines when the door is closed and the positions shown by the dotted lines when the door is opened.

At the bottom of the shaft cable 15 passes around a pulley 21 and then over a pulley 22 to which is secured the contact drum of safety switch 16. A freely suspended weight 23 is fastened to the lower end of the cable to keep it taut and to compensate for stretching and contraction, as will be hereinafter explained.

The amount the pulley and drum can be rotated is limited by a pair of fixed stops 24 and 25 which are adapted to be engaged by an arm 26 carried by pulley 22. Safety switch 16 has a pair of contacts 27 and 28 adapted to interconnect, respectively, two pairs of contacts 29 and 30 when the drum is in the position shown by the full lines and to disconnect them when the drum is in the position shown by the dotted lines.

The entire system can be fully understood

from a description of its operation, which is as follows:

When the elevator car door is closed, cable 15 extends vertically between the fixed rollers 17 and 18, weight 23 is in its lowermost position, and the drum of switch 16 is in the position shown by the full lines. Each pair of contacts 29 and 30 is thus interconnected.

10 In this condition current passes from the positive side of the line (+) through a conductor 35, contacts 29 of safety switch 16, a conductor 36 and an operating winding 37 of master switch 10 to the negative side 15 of the line (-). This closes the master switch 10. A circuit is also prepared from the positive side of the line (+) through conductor 35, contacts 30, and a conductor 38 to a movable arm 39 of the operator's controller. The closing of the master switch connects the line to the operator's-controller system. It also completes a circuit for the field winding of motor 6, from positive line, through a blade 40 of switch 10, a conductor 41, field winding 42, a conductor 43 and a blade 44 of switch 10 to negative line. The motor is thus subjected to full field excitation as long as the master switch is closed.

When the elevator is at rest the arm 39 of 30 the operator's-controller is in the mid position, as shown. If, now, the car door should be opened, the door-actuated lever 20 takes the position shown by the dotted lines and the cable is flexed, rotating the drum of 35 safety switch 16 in the direction of the arrow and elevating weight 23. The connection between contacts 29 and contacts 30 is, consequently, broken. The breaking of the connection between contacts 29 interrupts 40 the circuit for winding 37 of master switch 10. The master switch thereupon opens and entirely disconnects the motor and direction switches 8 and 9 from the line. The breaking of the connection between contacts 30 in- 45 terrupts the circuit to the arm 39 of the operator's-controller. It is thus impossible to start the car until the door is closed.

After the car door is closed the elevator is raised and lowered as follows:

50 If, for example, the car is to ascend, arm 39 of the operator's-controller is moved into engagement with a fixed contact 46. The partially completed circuit from positive line to arm 39 is thus closed through an operating winding 47 of direction switch 8, a conductor 48, a pair of fixed contacts 49 and a movable contact 50' of accelerating switch 11, conductor 43 and blade 44 of master switch 10 to negative line. The closing of 55 this circuit operates switch 8, which is provided with three pairs of fixed contacts 50, 51 and 52, and corresponding movable bridging contacts 53, 54 and 55. The movement of direction switch 8 upon the energization 60 of its winding interconnects the respective

pairs of contacts 50 and 51 and breaks the connection between the pair of contacts 52. The interconnection of contacts 50 and contacts 51 completes an operating circuit for the armature of motor 6 from positive line, through blade 40 of master switch 10, conductor 41, contacts 50, conductors 56, 57, 58 and 59, armature 60 of motor 6, conductors 61, 62 and 63, contacts 51, conductors 64 and 65, starting resistances 66, 67, 68 and 69, conductor 43 and blade 44 of master switch 10 to negative line. The motor armature is thus connected to the line in series with all of the starting resistance. The breaking of the connection between contacts 52 performs a function to be hereinafter explained.

The windings of the accelerating switches 11, 12, 13 and 14 are connected in parallel across the motor armature. The switches are so adjusted that, as the motor speed increases and its counter-electromotive force consequently increases, they are successively operated to exclude the starting resistances. Thus when the motor speed has accelerated a predetermined amount, switch 11 is operated and resistance 66 is short circuited. Further acceleration to a predetermined speed operates switch 12 and resistance 67 is also shortcircuited. This successive action continues until the operation of accelerating switch 14 shortcircuits the last starting resistance 69 and the motor armature is directly across the line.

The motor has thus been started in the up direction and accelerated until it is elevating 100 the car at full speed.

To cause the elevator car to descend, the controller arm is moved to engage a fixed contact 72, which completes a circuit through an operating winding of direction switch 9. The various steps in starting and accelerating the motor, as previously described, are repeated, except that the motor armature connections are reversed and current flows through the armature in the reverse direction.

To stop the car in either direction by the operator's-controller, arm 39 is moved to its mid position. Switch 8 or switch 9, depending upon whether the car was ascending or descending, is thereupon deenergized, the armature connections to the line are broken, and, as the motor speed decreases, the accelerating switches are deenergized and return to normal position. In order to overcome 120 the momentum of the car and motor and prevent coasting the motor is caused, momentarily, to act as a generator to provide dynamic braking. This is accomplished by establishing a partial shortcircuit for the 125 armature through conductor 61, a resistance 73, a conductor 74, contacts 52 of switch 8, corresponding contacts 75 of switch 9, and conductor 59 back to the armature. This partial shortcircuit of the motor armature, since 130

there is no interruption in the field connections across the line, provides dynamic braking to prevent excessive coasting of the car. This shortcircuit is broken by the energization of either switch 8 or switch 9 disconnecting the respective contacts 52 or 75. There is, thus, no shortcircuiting of the line at the time it is connected to the armature by one of the direction switches.

10 If, during the ascending of the car, the door should be opened, the lever 20 is moved to the dotted line position. This movement of lever 20 flexes the cable, rotating pulley 22 and the drum of safety switch 16 in the 15 direction of the arrow and disconnecting contacts 29 and 30, as before. The disconnection of contacts 30 opens the circuit for the winding of direction switch 8. Switch 8 returns to normal position, interrupting 20 the line connections to the motor armature and providing the dynamic brake shortcircuit, through resistance 73, as previously described.

In order that the motor may act as a generator to secure the proper dynamic braking action, it is necessary to maintain the field excitation of the motor until the car is stopped. This is accomplished by retaining the master switch closed in spite of the 30 fact that the circuit for its winding through contacts 29 has been opened by the rotation of the drum of the safety switch. The master switch has an auxiliary pair of contacts 76, which are closed when the master 35 switch is closed and open when the master switch is open. Accelerator switch 14 also has a pair of stationary contacts 77 adapted to be interconnected by a movable contact 78 when the switch is energized. These two 40 sets of contacts control a by-pass circuit for winding 37, including conductors 79 and 80, which is independent of contacts 29. Thus, when the master switch has once been closed, it is independent of safety switch 16 45 as long as accelerator switch 14 is energized. When, therefore, power is removed from the operating motor by the opening of the door during the movement of the car, the master switch remains closed and dynamic braking 50 action is provided until the motor has so decreased its speed that accelerator switch 14 is deenergized. The accelerating switches are usually deenergized at a considerably lower current value than that at which they 55 are operated so that the desired braking action can be readily obtained. The auxiliary switch need not be placed on the last accelerator switch but may be associated with any of the accelerating switches.

60 The master switch can be readily arranged to be placed in a cabinet which can be made inaccessible to the ordinary cleaner and repairman. By having the by-pass circuit include contacts 76, it is thus impossible for 65 the inadvertent manual manipulation of the

accelerating switches, during inspection, cleaning, repairs, etc., to start the car while the door is open. The inadvertent interconnection of contacts 77 can have no effect upon the master switch unless that switch 70 is closed, and the closing of the master switch is impossible unless the car door is closed.

In order to prevent the motor from being thrown upon the line without all the starting 75 resistance in circuit, as might be the case if the operator could, by quickly reversing the position of arm 39 of his controller, connect the motor armature in circuit in a reverse direction before the accelerating switches are 80 deenergized, the energizing circuits of the windings of direction switches 8 and 9 pass through contacts 49 on accelerating switch 11. These contacts are shunted by a resistance 81, which is sufficiently high to prevent 85 the operation of the switches 8 or 9 when it is in series with their operating windings. The shortcircuiting of this resistance by the deenergizing of accelerating switch 11 allows sufficient current to flow, when controller arm 39 is made to engage contacts 46 or 72, to effect the operation of direction switch 8 or 9. Thus the operator cannot connect the motor to the line without all 90 of the starting resistance being in circuit. 95

Fig. 2 shows a modified arrangement for controlling the master switch by-pass circuit, to insure dynamic braking when the door is opened while the car is in motion. Instead of having the by-pass circuit controlled by contacts on one of the accelerating switches, a counter voltage relay 82 may be connected across the motor armature. A pair of fixed contacts 83 and 84 of relay 82 are connected, respectively, to 100 the positive line and the righthand auxiliary contact 73. These contacts then bear the same relation to the by-pass circuit as do contacts 77 when the accelerating switch is used for the control. When the counter 105 voltage relay 82 is sufficiently energized by the counter-electromotive force of the motor, its armature interconnects contacts 83 and 84, closing the by-pass circuit of the master switch with the same result as previously 110 described. The counter voltage relay arrangement is particularly adapted for equipments where the safety control is added to existing installations. No change need be made in the accelerating switches already 115 in place. It is also particularly adapted for elevator equipments which depend upon other means than counter voltage accelerating switches for controlling the motor current. 120

The stretching and contraction of cable 15 is automatically compensated for by having the cable pass over the pulley 22 of safety switch 16 and held taut by a freely suspended weight. The drum in being moved to its 130

normal position by the pull of the weight is always stopped in a definite position by arm 26 engaging stop 25. The weight, 5 exerating a constant pull on the cable, thus maintains a constant tension on the cable, which slips on pulley 22 just enough to be kept taut. The lengthening or shortening of the cable, therefore, has no injurious effect upon the operation of the safety switch.

10 The violent or repeated opening of the door might, because of the momentum of the drum switch, cause the cable to slip over pulley 22 far enough in the reverse direction to prevent the subsequent interconnection of contacts 29 and contacts 30 when the door is closed. This would prevent the operation of the elevator even though the door was shut. Such a condition is obviated by providing the stop 24 in such a position 15 that it is engaged by arm 26 upon a small movement of the drum caused by a slight opening of the door. During the remainder of the flexing of the cable caused by the completion of the opening of the door the 20 cable slips on pulley 22. Whenever the door is closed there is, therefore, enough movement of the cable to insure that arm 26 will engage stop 25, in which position contacts 29 and contacts 30 are interconnected 25 and the elevator may be started. By the proper spacing of stops 24 and 25 the correct positioning of the interconnecting contacts 27 and 28 is insured for both the open and closed conditions of the door. It has 30 been found that satisfactory results can be obtained by having the stops comparatively close together and arranging the contacts so that interconnection and disconnection are accomplished by a slight rotation of pulley 35 22. The desired friction of cable 15 upon pulley 22, to insure proper operation of the drum safety switch and not to render the movement of the door difficult, can be obtained by making the pulley 21 adjustable 40 in an upward and downward direction so that the amount of the circumference of pulley 22 engaged by the cable can be increased or decreased.

45 In case cable 15 should break while the door is closed, a counter-weight 85 moves the drum of safety switch 16 in the direction of the arrow, breaking the connections between contacts 29 and contacts 30. Master switch 10 is, thereupon deenergized and the 50 car cannot be operated until the cable is repaired. If the cable breaks while the car is running, it is immediately stopped. In case the break occurs while the door is open, and consequently the connections between 55 contacts 29 and 30 are already broken, counter-weight 85 holds the drum of safety switch 16 in that position. The master switch cannot be closed and the elevator cannot be started. Other means than a counter- 60 weight may be used to rotate the drum of 65

safety switch 16 when the cable breaks. For example, a spring acting in opposition to weight 23 may be employed.

70 While the invention has been described in connection with one type of electrical elevator equipment, it will be readily understood that it may be employed with other types and that its use is not confined to electrically operated elevators.

75 The shaft and car doors may be suitably interlocked, so that both must be closed before the elevator can be operated. One form of interlock is disclosed in my Patent No. 1,293,668, granted Feb. 11, 1919.

80 The invention claimed is:

85 1. An elevator control having a source of power for raising and lowering the elevator car, an electromagnetic switch for controlling said source in raising the car, an electromagnetic switch for controlling said source in lowering the car, means actuated by the car operator for controlling both said electromagnetic switches, a safety switch for causing the operation of either electromagnetic switch to prevent further movement 90 of the car independently of said means, and a member extending along the elevator shaft and operable by the movement of the car door in any position of the car to control said safety switch.

95 2. An elevator control comprising a master switch for controlling the application of power to the elevator car, a safety switch for controlling said master switch, and a cable extending along the elevator shaft and 100 operated by the car door for controlling said safety switch, whereby the application of power to the elevator is under the control of the door thereof.

105 3. An elevator control comprising an electromagnetic master switch for controlling the application of power to the elevator motor, safety mechanism under the influence of the elevator door for controlling said master switch, and means dependent upon the operating conditions of the elevator motor for modifying the control of said safety mechanism over said master switch.

110 4. An elevator control comprising an electromagnetic master switch for controlling the application of power to the elevator, acceleration control means for governing the speed of the elevator, safety mechanism under the influence of the elevator door for controlling said master switch, and means associated with said acceleration control means for modifying the control of said safety mechanism over said master switch.

115 5. An elevator control having mechanism for raising and lowering the elevator car, a cable extending along the elevator shaft and 120 actuated by the car door for controlling said mechanism, and means for automatically compensating for stretching or contraction of said cable.

6. An elevator control having mechanism for operating the elevator car, a cable extending along the elevator shaft and actuated by the car door for controlling said mechanism, and means for automatically maintaining the operative relation between said cable and said mechanism. 5
7. A control for elevator operating means comprising a cable extending along the elevator shaft and under the control of the car door, safety mechanism controlled by said cable for preventing the operating means from moving the car when the door thereof is open, and means for causing said safety mechanism to prevent movement of the elevator if the cable breaks. 10
8. An elevator control having mechanism for raising and lowering the elevator car, a flexible cable fixed at one end and extending along the elevator shaft and controlled by the open and closed condition of the car door, a safety switch including a rotatable member for controlling said mechanism, said rotatable member being controlled by said cable, and a weight connected with the free end of the cable for automatically compensating for stretching or contraction of said cable. 20
9. An elevator control having mechanism for raising and lowering the elevator car, a flexible cable extending along the elevator shaft and controlled by the open and closed condition of the car door, a safety switch, including a rotatable member, for controlling said mechanism, said rotatable member being controlled by said cable, means for limiting the movement of the rotatable mem- 30
- ber in either direction, and means associated with the cable and coöperating with said limiting means for automatically maintaining the operative relation between the cable and said safety switch. 40
10. An elevator control having mechanism for raising and lowering the elevator car, a flexible cable extending along the elevator shaft and actuated by the car door, a safety switch controlled by said cable and controlling said mechanism, said safety switch including a rotatable contact carrying drum engaged by said cable. 45
11. A control for elevator operating means comprising a cable extending along the car shaft and under the control of the car door, safety mechanism including a switch mounted on a drum and controlled by said cable for causing the operating means to stop the car when the car door is opened, and a weight coöperating with the drum to cause the switch to open if the cable breaks. 50
12. A control for elevator operating means comprising a cable extending along the car shaft and under the control of the car door, a switch controlled by said cable to cause the operating means to stop the car at any point of the shaft if the door is opened, said switch comprising a drum, contacts thereon, stops to limit the movement of the drum in each direction, and means for varying the arc of contact of the cable with the drum to permit the cable to freely slide over said drum after engaging a stop. 60

In witness whereof I have hereunto subscribed my name.

EDWIN F. BANFIELD.
